CLAIM

We claim the ornamental design for a waste disposal device cover, as shown and described.

DESCRIPTION

FIG. 1 is a front perspective view of a waste disposal device cover showing our new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The stippled shading in the figures is fragmentarily shown for convenience of illustration, it being understood that the stippled shading is uniformly continued over the surface on which it appears.

The broken lines shown in the figures are included for the purpose of illustrating environment and form no part of the claimed design.
